[57] CLAIM

The ornamental design for a draining canister holder, as shown and described.

DESCRIPTION

FIG. 1 is a perspective view of a draining canister holder showing my new design;

FIG. 2 is another perspective view;

FIG. 3 is a rear elevational view;

FIG. 4 is a bottom plan view;

FIG. 5 is a top plan view;

FIG. 6 is a right side elevational view which is a mirror image of the left side;

FIG. 7 is a front elevational view;

FIG. 8 is another perspective view; and,

FIG. 9 is another perspective view.

The broken-line disclosure of an oil filter, screw and fragmentary surface in FIG. 1, bottle in FIG. 8, and funnel in FIG. 9 are for illustrative purposes only and form no part of the claimed design.
